CLAIM

The ornamental design for an audio visual cart, as shown and described.

DESCRIPTION

FIG. 1 is a perspective elevation view of the audio visual cart showing our new design;

FIG. 2 is a side elevation view of the cart of FIG. 1, the opposite side elevation view being a mirror image of FIG. 2; FIG. 3 is a front elevation view of the cart of FIG. 1, the rear elevation view being a mirror image of FIG. 3;

FIG. 4 is a top plan view of the cart of FIG. 1; and,

FIG. 5 is a bottom plan view of the cart of FIG. 1.

The broken line showing of the wheels and the wheel locks is for illustrative purposes only and forms no part of the claimed design.
